UNITED STATES PATENT OFFICE.

HENRY G. HOGG, OF WINTHROP, MASSACHUSETTS.

DESIGN FOR A CHILD'S CAR.

53,125.

Specification for Design.

Patented Mar. 25, 1919.

Application filed September 25, 1918. Serial No. 255,727. Term of patent 3½ years.

To all whom it may concern:

Be it known that I, HENRY G. Hogg, a subject of the King of Great Britain, residing at Winthrop, county of Suffolk, State of Massachusetts, have invented a new, original, and ornamental Design for a Child's Car, of which the following is a specification, reference being had to the accompanying drawing, forming a part thereof.

In the drawing Figure 1 illustrates the

article in perspective; Fig. 2 is a rear elevation of the article.

The car embodying the design is symmetrical with respect to its central vertical plane.

I claim:

The ornamental design for a child's car as shown.

HENRY G. HOGG.
